UNITED STATES PATENT OFFICE.

GUSTAVE E. W. MILLER, OF BOSTON, MASSACHUSETTS, ASSIGNOR TO MILLER SAFETY TOOTH BRUSH COMPANY, OF BOSTON, MASSACHUSETTS.

BRUSH CASING AND HANDLE.

Application filed November 22, 1916, Serial No. 132,898. Renewed April 6, 1921. Serial No. 459,013.

To all whom it may concern:

Be it known that GUSTAVE E. W. MILLER, a citizen of the United States, residing at Boston, in the county of Suffolk and State 5 of Massachusetts, have invented a new and useful Brush Casing and Handle, of which the following is a specification.

This invention relates to that type of brush casings and handles so formed as to hold the brush either enclosed within or 10 projecting from the end thereof, so that the casing in the latter case will constitute a handle for the brush, and it relates more particularly to that variety of brushes shown in 15 my prior Patent No. 1,054,017, granted Feb. 25, 1913.

The principal objects of the invention are to improve the construction of this type of casing in order to render it more sanitary 20 than heretofore; to provide a casing or handle which can be opened readily for removing or inserting the brush and which will contain no part having a very deep cavity so that it can be manufactured inex- 25 pensively and thoroughly cleaned without trouble; to provide a construction of such a character that it will not tend to collect particles or dirt in any place that is not readily accessible; and especially to pro- 30 vide an improved way of hinging the parts together so that they will constitute a complete casing or handle which will be rigid and not likely to get out of position, and also which can be made of sheet metal, celluloid 35 or other light and thin materials without preventing such rigidity of construction. Further objects and advantages of the invention will appear hereinafter.

Reference is to be had to the accompanying drawings, in which—

Fig. 1 is a side elevation of a tooth brush constituting a preferred embodiment of this invention showing the parts in position for use;

Fig. 2 is a top view of the same with the two parts separated;

Fig. 3 is a side elevation showing the brush folded within the handle which is partly in section;

Fig. 4 is a side elevation; 50

Fig. 5 is a top view showing the parts open so that the brush can be removed;

Fig. 6 is a sectional view on the line 6—6 of Fig. 3 with the brush removed;

Fig. 7 is a side elevation of the end member with the side members removed to show the hinge construction;

Fig. 8 is an end view of the same;

Fig. 9 is a central longitudinal sectional view of the same; 60

Fig. 10 is an elevation of the wire hinge member, and

Fig. 11 is an edge view of the same.

I prefer to use certain features of my above mentioned patent, especially the means 65 whereby the shank 13 of the brush back 11 is held in an open ended socket 16 of an end member 20. The shank fits within the open ended socket either in its closed or open position and the shank is provided with a 70 longitudinal groove 14 on each side and a depression 15 in line with each of these grooves. The open ended socket is provided with projections 23, two in number in the present case preferably, for entering the 75 same. These parts are put together in the manner set forth in the above mentioned patent and do not constitute a part of this invention. It is to be understood, therefore, that this invention is not limited to these 80 particular features.

The end member 20 is not made as deep as in the above mentioned patent so that it can be more readily cleaned and the whole casing or handle is so arranged that it does 85 not have any deep portions which involve some trouble to manufacture and are hard to reach for cleaning purposes. Therefore, this end member is shortened considerably, although it is still formed as a single rigid 90 member made of sheet metal, celluloid or other suitable material. At its open end it is provided with a ring 30 of wire preferably formed in rectangular shape and secured to the end member 20 by closing two flaps 95 29 of the same around the wire at the top and bottom and cementing, soldering, or otherwise securing them back to the inside.

surface of the end member. These two flaps extend over only the top and bottom of the wire, and leave the wire bars between them to form two parallel longitudinal hinge pins 5 31 at the edges of the end member 20. On these hinge pins are pivotally mounted two side members 32 and 33. These are secured to the hinge pins by turning over end flaps 34 around the hinge pins and securing them 10 back to the flat surfaces of the side members.

One side member has flanges 35 which set 15 into the walls of the other end and of the end member 20 so that their external surfaces come flush when they are closed. One 20 of them also has integral projections 36 extending inwardly from opposite sides and the other has depressions 37 registering with them to receive the projections to assist in holding the parts together. It will be seen 25 also that the end edges of these members next to the end member 20 are square-cornered, and fit against the end of the same to prevent their swinging inwardly beyond a point at which their external surfaces are in 30 the plane of the corresponding surfaces of the end member 20. No further fastening device is needed ordinarily, but to insure its still more perfect closing and holding of the parts the member 32 is shown as provided 35 with a clip 38 extending over the end of the member 33 to further hold them. These two members are shown as perforated for the purpose set forth in my above mentioned patent.

From this it will be seen that a device is 40 provided which is thoroughly sanitary and which will not unduly collect particles of dirt or moisture and can readily be cleaned throughout its entire surfaces, and that a construction is also provided which permits 45 of the ready removal of the brush from the interior and its insertion in the other end of the open socket so as to use the casing as a handle. In spite of the fact that the casing 50 is made of three parts seemingly hinged together loosely yet they are sufficiently rigid when connected to furnish a proper grip for all necessary manipulations required in using the brush.

It will be understood, furthermore, that the device can be made of any desired materials and that the invention is not limited to tooth brushes as other types of brushes 55 can be arranged in the same way.

Although I have illustrated and described 60 only a single embodiment of the invention I am aware of the fact that many modifications can be made therein by any person skilled in the art without departing from the scope of the invention as expressed in the claims.

Therefore, I do not wish to be limited to 65 all the details of construction herein shown and described, but what I do claim is:—

1. As an article of manufacture a brush casing and handle comprising an end member having means for firmly holding the end of the shank of a brush and also receiving the bristles at that end of the brush only, and two side members hinged to opposite edges thereof on axes parallel with said edges for enclosing the remainder of the brush held by the end member. 70

2. As an article of manufacture, a brush casing comprising an end member adapted to receive the shank of a brush from within the same and to support the brush projecting therefrom, and two side members each hinged to opposite edges of the end member 80 to swing on parallel axes and adapted to close together in alignment with the end member to enclose the brush. 75

3. As an article of manufacture, a brush casing comprising an end member having a 85 socket for receiving the shank of a brush and holding it therein, said end member being provided with a pair of hinge pins at its outer edges, two side members hinged to said hinge pins for enclosing the brush, the 90 edges of one overlapping the other to hold them firmly together. 90

4. An article of manufacture of the class described, comprising an end member having an open-ended socket at one end for receiving the shank of a brush and holding it therein, said end member being provided with a pair of parallel hinge pins at its outer edges, two side members hinged to 100 said hinge pins for enclosing the brush, the edges of one overlapping the other to hold them firmly together so as to constitute a casing with the end member, and a clip on 105 one of said members for assisting in holding the parts together. 105

5. As an article of manufacture, a brush casing of the class described comprising an end member having an open-ended socket for receiving the end of a brush shank therein and having at the opposite end thereof a 110 wire of rectangular form, the sides of which are in the planes of the walls of said end member, two opposite edges of the end member being lapped over the wire and secured back to the inner walls of the member 115 to hold the wire in position, leaving the other two parallel sides of the wire frame exposed, and a pair of side members hinged to said exposed parts of the wire member. 115

6. An article of the class described, comprising an end member having a socket for receiving the end of a brush shank and having at the end a wire of rectangular form, two opposite edges of the end member being lapped over the wire and secured back to the 125 walls of the member to hold the wire in position leaving the other two parallel sides of the wire frame exposed, and a pair of side members hinged to said exposed parts of the wire member. 120 130

7. An article of the class described, comprising an end member having a socket for receiving the end of a brush shank and having at the end a wire surrounding its edge, 5 two opposite portions of the end member being folded over the wire and secured back to the walls of the member to hold the wire in position, leaving two portions of the wire also located opposite each other exposed, and a pair of side members hinged to said exposed portions of the wire member. 10
- In testimony whereof I have hereunto affixed my signature.

GUSTAVE E. W. MILLER.
